ADOLPHUS D. BRANHAM, OF ST. LOUIS, MISSOURI, ASSIGNOR TO AUTOMATIC REGISTER COMPANY, OF DOVER, DELAWARE, A CORPORATION OF DELAWARE.

AUTOMATIC FARE-REGISTER.

1,114,851.

Specification of Letters Patent.

Patented Oct. 27, 1914.

Application filed June 14, 1913. Serial No. 773,684.

To all whom it may concern:

Be it known that I, ADOLPHUS D. BRANHAM, a citizen of the United States of America, residing at the city of St. Louis, State of Missouri, have invented a certain new and useful Automatic Fare-Register, of which the following is such a full, clear, and exact description as will enable any one skilled in the art to which it appertains to make and use the same, reference being had to the accompanying drawings, forming part of this specification.

My invention relates to a fare register which will automatically register the coins passing through same, preferably by means of an electrically operated registering mechanism.

My invention consists of various novel features and details of construction, all of which are described in the following specification and pointed out in the claims appended hereto.

In the accompanying drawings, which illustrate one form of register made in accordance with my invention, Figure 1 is a front elevation; Fig. 2 is a section on the line 2—2 of Fig. 1; Fig. 3 is an enlarged section on the line 3—3 of Fig. 1; Fig. 4 is an enlarged horizontal section showing a detail of construction; Fig. 5 is an enlarged section on the line 5—5 of Fig. 4; and Fig. 6 is a front elevation of the parts shown in Figs. 4 and 5.

Like marks of reference refer to similar parts in the several views of the drawings.

10 represents the upper part of the casing which contains the coin controlling and contact making devices, as will be hereinafter more fully described.

11 represents the lower part of the casing containing the cash drawer 12, the registering mechanism 13 and the battery 14. The registering mechanism 13 may be of any suitable form and will not be described in detail as it forms no part of my invention except in combination with the other parts of the device.

The upper portion 10 of the casing is provided with a cap 15 having a coin slot 16 of such size as to permit the passage of the proper coins, in the present instance, five and ten-cent pieces. The coins, after passing down through the slot 16, strike an in-

clined plane 17, preferably of glass. After striking the inclined plane 17, the coins slide down into a narrow space between a front plate 18 and a rear plate 19. The front plate 18 is preferably made of glass so as to allow inspection of the coins while passing through the device. The inclined plate 17 terminates at such a point at the rear of the plate 18 that the coins will fall over into the space between the plates 18 and 19 by the action of gravity, thus minimizing the liability of the coins becoming wedged in this space. The coins, after entering the space between the plates 18 and 19, fall upon an inclined ledge 20 along which they roll downwardly and drop upon a second inclined ledge 21. The plate 19, adjacent to this second ledge 21, is provided with a number of openings 22 to allow the discharge of any particles of grit or dirt which might enter the device and interfere with the proper action of the coins. Adjacent to the end of the ledge 21, the plate 19 has pivoted to it a movable member 23 which normally forms an upward extension of the ledge 22. This member 23 is provided with a weight 24 which holds it in its normal position, and it is also supplied with a tail-piece 25 which is adapted to be thrown upward by the weight of the coin passing over the extension 23 so as to form a coin detent. As the coin leaves the extension 23, it comes into contact with an end 26 of a contact making device which will be more fully described hereinafter. After making contact with the end 26, the coin will drop on to a third ledge 27. In the case of a five-cent piece, the ledge 27 will carry the coin toward the right hand side of the machine and drop the same on to an inclined plane 28 which is normally held in position by a coil spring 30. The coin will thus be held in a position to be inspected by the conductor or other person in charge of the register. The coin may be released and allowed to drop into the cash drawer 12 by pressure upon a knob 31 extending through the front of the machine. In the case of the coin being a ten-cent piece, it will drop down through the slot 32 onto the ledge 27 and thus come into contact with the end 33 of a second contact making device.

In order to prevent the clogging of the

machine by the insertion of a coin intermediate in width between a five and ten cent piece, I form one edge of the slot 32 of a pivoted rail 34 which is held in position by means of a light spring 35, best shown in Fig. 6.

Secured to the rear face of the plate 19 is a block 37 of fiber or other insulating material. Pivoted to this block 37 is a contact 38 which is held against a stop 39 by a light spring 40. 41 is a lever also secured to the block 37 and carrying the end 36 hereinbefore referred to, which end projects through the opening 42 into the space between the plates 18 and 19. The end 26 of this lever 41 is held against the plate by means of a coil spring 43. Below the contact 38 and the lever 41 is a second contact 44 and lever 45 which are similar to the contact 38 and lever 41. The lever 45 carries the end piece 33, hereinbefore referred to, which end piece projects through the opening 46 in the plate 19. The contacts 38 and 44 are connected by means of a conductor 47 and the levers 41 and 45 are connected by means of a conductor 48. The conductor 47 is connected by means of a binding post 49 with the conductor 50 leading to one terminal of the registering device 13, and the conductor 48 is connected by means of a binding post 51 with a conductor 52 leading to one terminal of the battery 14.

The operation of my device is as follows: When a coin is dropped into the machine, it first passes down along the ledges 20 and 21 and is discharged against the end 26 of the lever 41. This causes the lever 41 to move on its pivot and bring its end into contact with the contact piece 38, thus closing the circuit through the registering device 13 and battery 14, so as to operate the registering device to register a fare. In case two coins are dropped into the machine at the same time, the tail-piece 25 will be raised up into the path of the second coin so as to preserve an appreciable interval of time between the contact of the first and second coins with the end 26 of the lever 41. In case the coin is a five-cent piece, it will be carried past the end 33 of the lever 45 without coming into contact therewith. In case the coin is a ten-cent piece, it will drop through the slot 32, thus coming into contact with the end 33 of the lever 45 and closing the circuit to register another fare.

In case a coin of a thickness between a five and ten-cent piece, for example a worn one-cent piece enters the passage 32, it will move the rail 34 laterally and pass through the machine without blocking the same.

Having fully described my invention, what I claim as new and desire to secure by Letters-Patent of the United States is:

5 1. In a fare register, the combination

with a registering mechanism, of a movable member in the path of the coin and controlling said registering mechanism, an upwardly inclined chute, a pivoted member forming a downwardly extending continuation of said chute, said member having a tail-piece forming a coin detent. 70

2. In a fare register, the combination with a registering mechanism, of a movable member in the path of the coin and controlling the registering mechanism, a downwardly inclined coin chute, a pivoted member forming an upwardly extending continuation of said chute, said member having a tail-piece forming a coin detent, said member being weighted to normally hold said tail-piece out of operative position. 75

3. In a fare register, the combination with registering mechanism, of a contact device controlling said registering mechanism, a second contact device also controlling said registering mechanism, and means for preventing coins of a predetermined thickness actuating said second contact device. 85

4. In a fare register, the combination with 90 a registering mechanism, of a movable member in the path of the coin and controlling the registering mechanism, a second movable member also controlling the registering mechanism, and means for preventing coins of a predetermined thickness from coming in contact with said second movable member. 95

5. In a fare register, the combination with 100 an electrically operated registering mechanism, of a movable member in the path of the coin, a second movable member also located in the path of the coin, means for preventing coins of a predetermined thickness from making contact with said second movable member, a switch in circuit with said registering mechanism and controlled by said first named movable member, and a second switch also in circuit with said registering mechanism and controlled by said second movable member. 105

6. In a fare register, the combination with a registering mechanism, of a movable member in the path of the coin and controlling said registering mechanism, a second movable member also controlling said registering mechanism, and an inclined support for receiving the coin after contact with said first movable member, said inclined support having a passage for dropping coins of less 115 than a predetermined thickness into contact with said second movable member. 120

7. In a fare register, the combination with a registering mechanism, of a movable member in the path of the coin and controlling said registering mechanism, a second movable member also controlling said registering mechanism, an inclined support for receiving the coin after contact with said first named movable member, said inclined 125 130

support' having a passage for dropping coins of less than a predetermined thickness into contact with said second movable member, and a laterally yielding rail carried at one side of said inclined support and forming a part of the coin supporting surface.

In testimony whereof, I have hereunto set my hand and affixed my seal in the presence of the two subscribing witnesses.
